UNITED STATES PATENT OFFICE.

HARRY EHLIG, OF PEARL RIVER, NEW YORK, ASSIGNOR TO GEORGE R. SWART & COMPANY, INC., OF NEW YORK, N. Y., A CORPORATION OF NEW YORK.

SHEET REGISTER.

Application filed February 25, 1921. Serial No. 447,835.

To all whom it may concern:

Be it known that I, HARRY EHLIG, a citizen of the United States, and a resident of Pearl River, in the county of Rockland and State of New York, have invented certain new and useful Improvements in Sheet Registers, of which the following is a specification, reference being made to the accompanying drawings, forming a part thereof.

10 My invention relates to certain improvements in registering mechanisms such as are particularly designed and adapted for use in connection with sheet-folders, sheet-feeders, printing presses and the like, for gaging the position of the successive sheets fed or delivered to such machines in registry with the operative parts thereof.

The objects of my invention are, among other things, to provide a mechanism for 20 side-registering the sheets after they have been forwarded to the front or drop guides of a simple and efficient construction which will seize the sheets positively and unfailingly with a minimum amount of sliding 25 contact between the parts of my improved mechanism and the surfaces of the advancing sheets. A further object is to provide a side-register mechanism, the parts of which may be readily shifted sidewise in the machine to which it is attached, and in which the movements of the clamping members in seizing the sheets may be regulated to suit the varying character and thickness of the sheets, the side-registering mechanisms also 30 being bodily adjustable to accommodate my improved sheet-seizing devices to sheets of varying sizes.

My improved sheet-register is also of a strong and durable construction, and presents other features of novelty and improvement whereby this mechanism is rendered simpler and otherwise better adapted and more convenient for use in side-registering the successive sheets in suitable timed relation with their forwarding movements, all as will be hereinafter set forth and particularly pointed out in the claims.

A preferred embodiment of my invention is illustrated in the accompanying drawings 45 in which—

Fig. 1 is a fragmentary front elevation of my improved sheet-registering mechanism just before the upper clamp shoe is raised to release the sheet which has been brought into 55 side-register against the side-gage;

Fig. 2 is a detail view similar to Fig. 1 after the operative parts have completed a sheet-registering stroke;

Fig. 3 is a fragmentary detail view showing the position of the operative parts controlling the raising and lowering of the upper clamp shoe, as they will appear when the sheet-registering mechanism is about to begin a registering stroke (or when in the extreme right-hand position illustrated in Fig. 1);

Fig. 4 is an enlarged detail plan view of the clamp shoe, adjustable guide block and fixed bracket to which the guide block is adjustably connected;

Fig. 5 is an enlarged sectional view taken on the line 5—5 of Fig. 4 looking in the direction of the arrow;

Fig. 6 is a similar view taken on the line 6—6 of Fig. 4 looking in the direction of the arrow;

Fig. 7 is a similar view taken on the line 7—7 of Fig. 4 looking in the direction of the arrow;

Fig. 8 is an enlarged sectional view taken on the line 8—8 of Fig. 1 looking in the direction of the arrow crossing the dotted line, and showing only the support for the sheet-clamping devices;

Fig. 9 is an end view, on an enlarged scale, looking from the left in Fig. 1 showing the cam-plate support and cooperating members;

Fig. 10 is a fragmentary plan view, on enlarged scale, showing the clamp, guide and associated parts in combination with a clamped sheet to be drawn sidewise into registry;

Fig. 11 is a diagrammatic side elevation of a sufficient portion of a printing or other like machine to show the coordinating action of my improved sheet-register with such machine; and

Fig. 12 is an enlarged detail view mostly in vertical section showing how a part of the clamp-operating mechanism is adjustably keyed to the oscillating shaft which operates the upper clamp shoe.

Similar numerals refer to similar parts throughout the several figures.

Referring to Fig. 1, the side frames 13 and 14 support the standards 15 and 16 respectively which carry the operative parts of my sheet-registering mechanism. Extending across the machine is the reciprocating

ing hollow bar 17 slidably journaled in the collars 18 and 19 mounted on the standards 15 and 16 respectively. The sheet-registering devices are adjustably supported on the 5 cross-bar 17 between the collars 18 and 19 by any suitable means capable of holding same in rigid position on the bar when properly adjusted. In the embodiment shown the supporting bracket 20 has the split jaws 21 10 and 22 formed in its upper portion to encircle the bar 17 as shown in Fig. 8, and these split jaws are drawn together to hold the bracket in any fixed position on the bar 17 by the screw bolt 23. When the bolt 23 15 is unscrewed the jaws 21 and 22 slide transversely on the bar 17 to effect the required lateral adjustment.

Referring to Figs. 1, 2 and 8, the bracket 20 has the depending arm 24, the lower end 20 of which carries the horizontally disposed plate 25 which forms the fixed lower member of the sheet-clamping devices, the advancing sheet sliding over this plate to strike the front guides (not shown). Journaled 25 in the arm 24 above the clamping plate 25 is the small stub-shaft 26 which carries the rock-arm 27 which is normally forced downwardly into contact with the plate 25 by the coil-spring 28, the tension of which 30 is regulated by the collar 29 as shown in Fig. 8. Pivoted on the free end of rock-arm 27 is the rock-pin 30 (shown in Figs. 4 and 7), which carries the rocking clamp shoe 31, this shoe being designed to have 35 contact with the upper surfaces of the sheets and to seize and clamp same in conjunction with the fixed clamping plate 25. The spring 32, coiled about the pin 30 and connected with the outer collar 33 and the sleeve 34 on which the clamp shoe 31 is mounted, 40 yieldingly maintains the heel 35 of the shoe 31 in continuous contact with the clamping plate 25 as shown in Fig. 2. The oppositely-extending lugs 36 and 37 are preferably integrally formed on the free end of the rock-arm 27, as shown in Fig. 4, to limit the 45 rocking movements of the shoe 31 on the pin 30 with respect to the plate 25.

Between the two side frames 13 and 14 are 50 arranged two mutually parallel cross-bars 38 and 39 as shown in Figs. 4, 6 and 7. Slidably mounted upon the bar 39 is the adjustable bracket 40 which is preferably secured to the bar 39 by top plate 41 and the screws 55 42. A screw-threaded bore 43 is drilled in the side of the bracket 40 as shown in Figs. 4 and 5 which bore is engaged by the screw bolt 44 the point of which engages with the bar 39 to hold the bracket 40 in fixed position after the required adjustment. Also 60 slidably mounted on the bar 39 and inside the bracket 40 as shown in Figs. 1, 2 and 4, is the adjustable guide block 45 having the horizontal channel 46 formed in its top surface through which the plate 25 is adapted

to travel laterally when the bar 17 which supports the sheet-registering devices is reciprocated as will be hereinafter described. On either side of the channel 46 are the side-gages 47 and 48 against which the sheet 70 is drawn for side-registry. Below the side gage 48 and extending laterally from the block 45 and suitably secured thereto as shown in Fig. 6 is the bracket 49 having the screw-threaded bore 50 formed transversely 75 therein as shown in Fig. 4. This bore 50 is engaged by the threaded bolt 51 which passes through the threaded lug 52 mounted on the bracket 40 which lug also carries the threaded bolt 44. The thumb-screws 53 and 80 54 are secured to the bolt 51 to turn same to make the relative lateral adjustments on the bar 39 between the bracket 40 and block 45 as will be readily understood. Mounted on the block 45 and extending forwardly over 85 the bar 38 as shown in Figs. 4 and 6 is the side guide plate 55 under which the sheet 56 is advanced before being side-registered. The vertical position of the plate 55 may be regulated by the screw 57 and the downwardly bent cross-plate 58 mounted on the block 45 as shown in Figs. 6 and 7 enables the sheet 56 to pass readily over the bar 38 onto the top surface of the block 45 under the impulse of the sheet-forwarding mechanisms. 90

Means are provided to transversely reciprocate the cross-bar 17 in timed relation with the advancing of the successive sheets in suitable position to be side-registered by 100 the sheet-seizing devices heretofore described. In the embodiment shown particularly in Figs. 1 and 11, the right end of the bar 17 carries the collar 59 having the depending pin 60 upon which the link 61 is 105 journaled; the other end of the link 61 is pivotally connected to the outer end of the rock-arm 63 mounted on the top of the vertical rock-sleeve 64 journaled on the upright shaft 65 carried by the bracket 66 suitably affixed to the side frame 14. The lower end of the sleeve 64 carries the horizontally disposed rock-arm 67, the upper end of which is pivotally connected to the rock-lever 68 by the link 69. The rock-lever 68 110 is journaled to the stub-shaft 70 secured to the frame 14, and the lower arm 71 of the rock-lever 68 carries the cam-roller 72 which is maintained in engagement with the cam 73 mounted on the main power-shaft 74 by the 120 spring pressed rod 75 pivoted at 76 to the arm 71 and also suitably connected by the sleeve 77 pinned to the side-frame 14.

Referring to Fig. 11, I have shown diagrammatically a form of mechanism whereby the bar 17 is reciprocated in timed relation with the sheet-forwarding devices. The main power shaft 74 carries the gear wheel 78 which rotates the gear 79 and in turn the gear 80 which revolves the lower 130

feed-roller 81; the upper feed-roller 82 is journalled on the rock-arm 83 carried by the stub-shaft 84 supported to the side-frame 14 by the standard 85. The rock-arm 83 is actuated through the shaft 84 by the arm 86 which carries the pivoted rod 87, the lower end of which is slotted about the shaft 74. The rod 87 carries the cam-roller 88 in engagement with the cam 89 secured to the shaft 74, whereby the rod 87 is reciprocated once during each revolution of the shaft 74 to bring the feed-rollers 81 and 82 in operative contact with the sheet to be advanced. The sheets are fed 15 to the feed-rollers 81 and 82 from a pile (not shown) on the feed-board 90, and are carried one by one from these feed-rollers forwardly to the sheet-registry devices by the tapes 91 passing around the feed roller 20 81 and the tape roller 92 as shown in Fig. 11.

The means for operating the sheet-clamping devices and in drawing the sheet laterally to effect the proper side-registry against the side-gages is directly operated 25 by the lateral reciprocations of the cross-bar 17 as just described. The mechanisms to accomplish this side-registry are best shown in the different parts of their cycle of movements in Figs. 1, 2 and 3 while 30 the structural details are also shown in an enlarged scale in Figs. 8, 9 and 10.

Referring more particularly to Figs. 1, 2, 3 and 9, the left end of the bar 17 carries the collar 93 secured to the end of the bar 35 17 by the pin 94 (Fig. 9). The collar 93 carries the diagonally disposed support 95, the angular position of which may be adjusted on the bar 17 by the screw-pin 96. Resting on the support 95 is the triangular-shaped cam-plate 97 pivoted at its apex on the screw-pin 96 as shown in Fig. 9; the 40 lower end of the plate 97 carries the cam-roller 98 which is adapted to engage the cam-face 99 formed in the bracket 100 which is adjustably secured to the outer end rock-shaft 101 by the screw 102. This rock-shaft 101 is journalled on its outer end in the support 95 as shown in Figs. 1, 2 and 3. Formed in the cam-plate 97 is the curved 45 slot 103 through which passes the thumb screw 104 to guide and maintain the plate 97 in proper position resting against the inclined face of the support 95. The rock-shaft 101 extends inwardly and transversely 50 of the machine with its inner end journalled in the block 105 secured to the bracket 20 through the arm 106 as shown in Figs. 8 and 10; adjacent the block 105 is the rock-sleeve 107 adjustably secured to the rock-shaft 101 by the key 108 as shown in Fig. 60 12. Preferably integrally formed on the sleeve 107 is the lip 109 which engages with its upper surface the roller 110 pivoted on the lug 111 extending upwardly from the 65 rock-arm 27 which roller 110 is normally in

contact with the lip 109 by the spring 28 as shown in Figs. 8 and 10.

The cam-roller 98 is caused to ride up and down over the cam-face 99 to cause the rock-shaft 101 to oscillate to raise the 70 clamp-shoe 31 when the cross-bar 17 is laterally reciprocated by devices best shown in Figs. 1, 2 and 3. The standard 15 carries the bracket 112 which supports the adjustable screw bolt 113 extending laterally 75 therefrom, and the standard 15 also has secured to it the horizontally disposed rod 114 screw-threaded at its outer end 115 on which the buffer plate 116 is adjustably mounted by nuts 117. The head of the bolt 80 113 is adapted to contact with the right shoulder of the cam-plate 97 when the cross-bar 17 is reciprocated to the right as shown in Fig. 3, to push the cam-plate to the left thereby carrying the cam-roller 98 85 off the high part of the cam-face 99, while the buffer plate 116 is adapted to contact with the left shoulder of the cam-plate 97 as shown in Fig. 2 to swing the cam-plate 97 from the position shown in Fig. 1 to the 90 right when the bar 17 is moved to the left as shown in Figs. 1 and 2, thereby causing the cam-roller 98 to ride up from the low to the high part of the cam-face 99 to depress same, thereby causing the rock-shaft 95 101 immediately to rotate in the direction of the arrow coiled about the shaft 101. Such oscillation of the shaft 101 lifts the clamp shoe 31 to release the sheet already 100 side-registered against the side-gage 48, the heel 35 remaining in contact with the plate 25 beyond the side-gage and out of the zone of the sheets through the tension of the spring 32. The relative distance between the screw-bolt 113 and buffer-plate 116 may 105 be regulated to adjust the duration of the action of the clamping members on the sheet during the left movement of the cross-bar 17 to meet the requirements as to the thickness and character of the sheets; Fig. 2 110 shows the action of the parts by which the clamp shoe 31 is positively raised out of contact with the sheet 56 after it has been drawn against the side-gages 47 and 48 as 115 shown in Figs. 1 and 2.

The operation of my sheet-register in conjunction with the sheet forwarding mechanisms shown in Fig. 11 is substantially as follows: When the cam-roller 88 is travelling on the high part of the cam 89 the upper feed-roller is raised and a sheet advanced by the feed-rollers from the pile in the table 90 has been forwarded by the tapes 91 against the front guides and the side-registry devices are operative. The cam-roller 72 is shown in the 120 drop of the cam 73 which indicates that the bar 17 has completed its registering stroke to the left (Fig. 2) and is about to be reciprocated to the right to be shifted into the proper position at the beginning of the 125 130

sheet-registering stroke (Fig. 3). When the cam-roller 88 reaches the drop of the cam 89, the feed-roller 82 is lowered to advance a sheet to the forwarding tapes 91. 5 After any sheet has been advanced by the tapes against the front guides (not shown) the sheet clamping devices proper (plate 25 and clamping shoe 31) are moved to the right as a unit with the clamp shoe 31 raised 10 as in Fig. 2 due to the fact that the cam-roller 98 rests on the high part of the cam-face 99 and hence has oscillated the rock-shaft 101 so as to raise the clamp shoe 31 against the tension of the spring 28 when 15 the shoe is maintained and raised as in Fig. 2. When the right shoulder of the cam-plate 97 strikes the screw-bolt 113, the cam-plate 97 is swung off centre to the left which causes the roller 98 to run down the cam- 20 face 99 thereby releasing the clamp shoe 31 which is snapp'd downwardly (assisted by gravity) on the side margin of the advanced sheet resting on the clamping-plate 25. The left movement of the bar 17 as shown in Fig. 25 1 in the direction of the arrow carries the sheet-clamping unit with the sheet 56 into side-registry with the side-gages 47 and 48, and a further movement of the bar 17 to its extreme left position shown in Fig. 2 carries 30 the left shoulder of the cam-plate 97 against the buffer-plate 116 thereby causing the cam-plate 97 to swing to the right as shown in Fig. 2 which swinging movement carries the cam-roller 98 up on the high part of the cam-face 99 and depresses the latter and so rocks the shaft 101 as to lift the clamp shoe 31 against the tension of the spring 28, all as 35 shown in Fig. 2; it is clear also that such shoe is held in its raised position while being moved to the right to begin another cycle in side-registering the next sheet.

By the structure shown in the figures, the requisite lateral adjustment of the supporting bracket 20 on the bar 17 can be accomplished by the screw-bolt 23 while the complementary adjustments of the lug 105 and sleeve 107 on the rock-shaft can be made by shifting the key 108 transversely on the shaft 101. In like manner a delicate adjustment of the side gages with the normal line of the side edges of the successive sheets can be made in either direction by actuating the screws 53 and 54. I have already explained that the relative distances between the head 55 of the screw-bolt 113 and the buffer plate 116 may be increased or diminished by adjusting either bolt or plate, which distance will directly affect the action of the clamp shoe 31 in seizing and releasing the sheets; 60 this feature is of advantage in properly side-registering sheets of different character and thickness.

While the construction set forth herein embodies the invention in its preferred form, 65 many changes and variations may be made

therein without departing from the underlying principles and advantages disclosed therein; and it is to be understood that while these improvements are particularly adapted for use in connection with sheet-feeding machines they may be employed in other relations. While the preferred use of my improved sheet-register is for side-registering the sheets as shown and described, it is manifest that my improvement may also be employed for front-registering the sheets before being advanced to a printing or other like machine.

I claim as my invention:

1. In a sheet-register, an upper oscillatable clamp shoe and means, separate from, and out of contact with, said shoe when engaging the sheet, to limit its oscillation in either direction.
2. In a sheet-register, an upper oscillatable clamp-shoe having means to limit the oscillation in either direction, and means yieldingly pressing the heel of said shoe downwardly.
3. In a sheet-register, a reciprocatable sheet-clamping mechanism comprising a horizontally disposed clamp plate and an oscillatable clamp shoe to coact with said plate to seize the sheets, and means at all times yieldingly pressing the heel of said shoe on said plate.
4. In a sheet-register, a reciprocatable sheet-clamping mechanism comprising a horizontally disposed clamp plate and a superimposed, vertically movable, normally lowered oscillatable clamp shoe to coact with said plate to seize the sheets, and means at all times yieldingly pressing the heel of said shoe on said plate.
5. In a sheet-register, a reciprocatable sheet-clamping mechanism comprising a horizontally disposed clamp plate and a superimposed, vertically movable, normally lowered oscillatable clamp shoe to coact with said plate to seize the sheets, means at all times yieldingly pressing the heel of said shoe on said plate, and means to raise said rock arm operable when said clamping mechanism is reciprocated.
6. In a sheet-register, a side-gage, a front guide plate, a reciprocatable sheet-clamping mechanism to draw the sheets against the side-gage, and means to move said side-gage and guide plate as a unit laterally in either direction independently and without varying the action, of the sheet-clamping mechanism.
7. In a sheet-register, a sheet-clamping mechanism having a vertically movable clamp shoe normally held depressed, means to reciprocate said sheet-clamping mechanism including means to raise said clamp shoe, and means to vary the timing of said clamp-shoe raising means in each cycle.
8. In a sheet-register, a sheet-clamping

- mechanism having a vertically movable clamp shoe normally held depressed by a spring, means to reciprocate said sheet-clamping mechanism including means to raise said clamp shoe against the tension of said spring, and means to vary the timing of said clamp-shoe raising means in each cycle.
9. In a sheet-register, a side-gage, a sheet-clamping mechanism having a vertically movable clamp shoe normally held depressed, means to move said sheet-clamping mechanism to and from said side-gage, means to raise said clamp shoe when said last means moves toward said side-gage, and means to vary the timing of said clamp-shoe raising means in each cycle.
10. In a sheet-register, a side-gage, a sheet-clamping mechanism having a vertically movable clamp shoe normally held depressed by a spring, means to move said sheet-clamping mechanism to and from said side-gage, means to raise said clamp shoe against the tension of said spring when said last means moves toward said side-gage, and means to vary the timing of said clamp-shoe raising means in each cycle.
11. In a sheet-register, a side-gage, a sheet-clamping mechanism having a vertically movable clamp shoe normally held depressed, means to move said sheet-clamping mechanism to and from said side-gage, means to raise said clamp shoe when said last means moves toward said side-gage, said means holding said clamp shoe raised when moved away from said side-gage, and means to vary the timing of said clamp-shoe raising means in each cycle.
12. In a sheet-register, a side-gage, a sheet-clamping mechanism having a vertically movable clamp shoe normally held depressed by a spring, means to move said sheet-clamping mechanism to and from said side-gage, means to raise said clamp shoe against the tension of said spring when said last means moves toward said side gage, said means holding said clamp shoe raised when moved away from said side-gage, and means to vary the timing of said clamp-shoe raising means in each cycle.
13. In a sheet-register, a side-gage, a sheet-clamping mechanism having a vertically movable clamp shoe normally held depressed, means to move said sheet-clamping mechanism to and from said side-gage, means to raise said clamp shoe when said last means moves toward said side-gage, said means holding said clamp shoe raised when moved away from said side-gage, means to release said clamp-shoe raising means, and means to vary the timing of said clamp-shoe raising means in each cycle.
14. In a sheet-register, a side-gage, a sheet-clamping mechanism having a vertically movable clamp shoe normally held de-
- pressed, means to move said sheet-clamping mechanism to and from said side-gage, means to raise said clamp shoe when said last means moves toward said side-gage, said means holding said clamp shoe raised when moved away from said side-gage, means to release said clamp-shoe raising means, and means to vary the timing of said clamp-shoe raising means in each cycle.
15. In a sheet-register, a sheet-clamping mechanism, means to reciprocate same in registering the sheets, and means comprising two swinging cam members coacting in transverse planes for opening said sheet-clamping mechanism.
16. In a sheet-register, a sheet-clamping mechanism, means to reciprocate same in registering the sheets, and means comprising two swinging cam members coacting in transverse planes for opening said sheet-clamping mechanism and maintaining same in open position.
17. In a sheet-register, a sheet-clamping mechanism, means to reciprocate same in registering the sheets, means comprising two swinging cam members coacting in transverse planes for opening said sheet-clamping mechanism, and means to vary the timing of said opening means.
18. In a sheet-register, a sheet-clamping mechanism, means to reciprocate same in registering the sheets, and means comprising two swinging cam members coacting in transverse planes for opening and closing said sheet-clamping mechanism.
19. In a sheet-register, a sheet-clamping mechanism, means to reciprocate same in registering the sheets, and means comprising two swinging cam members coacting in transverse planes for opening and closing said sheet-clamping mechanism and maintaining same in open position.
20. In a sheet-register, a sheet-clamping mechanism, means to reciprocate same in registering the sheets, means comprising two swinging cam members coacting in transverse planes for opening and closing said sheet-clamping mechanism, and means to vary the timing of said opening and closing means.
21. In a sheet-register, a side-gage, means for advancing the leading edge of the sheet beyond said side-gage, reciprocatable sheet-clamping means to draw said sheet against said side-gage, and means to move said side-gage laterally in either direction without varying the action of said sheet-clamping means.
22. In a sheet-register, a side-gage, means for advancing the leading edge of the sheet beyond said side-gage, reciprocatable sheet-clamping means to draw said sheet against said side-gage, and means to move said side-gage laterally in either direction independ-

ently and without varying the action of said sheet-advancing or sheet-clamping means.

23. In a sheet-register, a side-gage, means for advancing the leading edge of the sheet beyond said side-gage, reciprocatable sheet-clamping means to draw said sheet against said side-gage, and means to move said side-gage laterally in either direction independently and without varying the action of the sheet-clamping reciprocating means.

24. In a sheet-register, a side-gage, means for advancing the leading edge of the sheet beyond said side-gage, sheet clamping means comprising a normally lowered oscillatable clamp-shoe to bear on the top surface of the sheet, means for moving the sheet-clamping means laterally to draw the sheet against the side-gage, and means, comprising two

swinging cam members coacting in transverse planes and actuated by said sheet-clamping moving means to raise said clamp-shoe from the sheet.

25. In a sheet register, a side-gage, means for advancing the leading edge of the sheet beyond said side-gage, sheet clamping means comprising a normally lowered oscillatable clamp-shoe to bear on the top surface of the sheet, means for moving the sheet-clamping means laterally to draw the sheet against the side-gage, and means, comprising two swinging cam members coacting in transverse planes and actuated by said sheet-clamping moving means to raise and hold said clamp-shoe from the sheet upon the return stroke of said sheet-clamping means.

HARRY EHLIG.
